(57) **CLAIM**

The ornamental design for a driver assistance system terminal, as shown and described.

DESCRIPTION

FIG. 1 is a front, top, left side perspective view of a driver assistance system terminal showing my design.

FIG. 2 is a rear, bottom, right side perspective view thereof.

FIG. 3 is a front, top, left side perspective view of thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof; and,

FIG. 10 is an enlarged view thereof, taken from portion 10 in FIG. 3.

The broken lines in the drawings illustrate portions of the driver assistance system terminal that form no part of the claimed design. The dot-dash broken lines in FIG. 3 and

(Continued)

FIG. 10, the number “10” in FIG. 3 are included to show a partially enlarged view only and form no part of the claimed design.

1 Claim, 10 Drawing Sheets
